HARVEY J. LOUNSBURY, OF GLEN ELLYN, ILLINOIS, ASSIGNOR TO W. H. MINER, INC., OF CHICAGO, ILLINOIS, A CORPORATION OF DELAWARE

YOKE

Application filed December 24, 1926. Serial No. 156,779.

This invention relates to improvements in means for connecting the drawbar to the draft yoke in railway draft riggings.

One object of the invention is to provide a simple and efficient means for connecting the drawbar and draft yoke of a railway draft rigging, wherein ready attachment and detachment of the drawbar to the yoke is provided for.

Another object of the invention is to provide means for detachably connecting the drawbar to the yoke of a railway draft rigging, including a holding element, wherein the butt end of the drawbar co-operates with the holding element to prevent displacement of the latter and lock it to the yoke.

A more specific object of the invention is to provide a means for connecting the drawbar to the yoke of a railway draft rigging, wherein the drawbar is held attached to the yoke by a locking element fitting in transverse slots in the head end of the yoke and the locking element is held against lateral displacement by engagement of the butt of the drawbar with abutment means on said element.

Other objects and advantages of the invention will more fully and clearly appear from the description and claims hereinafter following.

In the drawing, forming a part of this specification, Figure 1 is a side elevational view of a drawbar and yoke illustrating my improvements in connection therewith. Figure 2 is a horizontal, sectional view corresponding substantially to the line 2-2 of Figure 1, showing the butt end of the drawbar in dotted lines. And Figure 3 is a transverse vertical sectional view corresponding substantially to the line 3-3 of Figure 1, also showing the butt of the drawbar in dotted lines.

As shown in the drawings, my improvements comprise broadly: a yoke A; a drawbar B; and a locking element C.

The yoke A has the usual upper and lower arms 10 and 11 and a rear end connecting piece 12. At the forward end, the yoke is provided with a hooded head 13 having vertically disposed spaced side walls 14-14 and

top and bottom walls 15-15 forming extensions of the top and bottom arms 10 and 11 of the yoke. The top wall 15 at the outer end thereof is provided with a downturned flanged section 16 which presents a short vertical shoulder co-operating with the drawbar butt in a manner hereinafter explained. The front end of the bottom arm 11 of the yoke is downwardly offset as indicated at 17 and merges with the bottom wall 15 of the hood. As clearly shown in Figure 1, the lower section of the hood is enlarged, the enlargement projecting forwardly to provide additional strength at this portion of the yoke. The side walls are slotted in transverse alignment as indicated at 18-18 to accommodate the locking element or block C, the slots 18 being preferably of L shape as clearly shown in Figure 1.

The drawbar B is of the usual form and has an enlarged butt end 19 which is shouldered at the top and bottom as indicated at 20-20. The upper shoulder 20 is adapted to engage behind the flange 16 at the top of the yoke to prevent outward movement of the drawbar when the parts are locked in assembled position. The opening at the forward end of the hood between the flange 16 and the bottom wall 15 is of such a size as to permit the insertion of the drawbar butt through the front end of the yoke.

The locking element or block C is in the form of a relatively heavy plate-like member having an upstanding transverse flange 21, thereby providing an L-shaped member corresponding to the shape of the slots 18. The upstanding flange 21 presents a transverse rear abutment face adapted to co-operate with the lower abutment shoulder 20 of the drawbar B. The block C is insertible transversely of the yoke through the slots 18 and is held fixed against movement in a direction lengthwise of the yoke by the front and rear end walls of the slots 18. As clearly shown in Figures 1 and 3, the slots 18 are so arranged that the bottom walls thereof are in alignment with the upper surface of the bottom wall 15 of the hood, whereby the locking element C will bear directly on the wall 15 when in position. The top surface of the

locking block C is centrally recessed or slotted as indicated at 22, thereby providing longitudinally extending vertical side abutment faces 23—23. The opening or slot 22 is of a width to accommodate the lower portion of the butt 19 of the drawbar. The bottom wall of the opening or slot 22, as clearly indicated in Figure 1, is in substantial alignment with the upper surface of the main portion of the arm 11 of the yoke and the distance between the inner surface of the top wall 15 of the hood and the surface of the bottom wall of the slot 22 is such as to substantially correspond to the height of the butt 19 of the drawbar, so that when the parts are assembled, the drawbar butt will be held against vertical movement to any great extent, thereby preventing disengagement of the shoulders 20 from the flanges 16 and 21.

20 The vertical end section 12 of the yoke is cut away at opposite sides at the top and bottom as indicated at 24—24, thereby providing central vertical webs and a relatively broad abutment surface 25 therebetween corresponding in width to the width of the yoke. Rearwardly of the abutment member 25, the sides of the section 12 are also cut away as indicated at 26, thereby leaving a central vertical web. The webs 24 are cut away or notched as indicated at 27 adjacent the top and bottom arms of the yoke.

As is well known in the art, the yoke A is adapted to accommodate the usual shock absorbing mechanism employed in railway draft riggings, the shock absorbing mechanism being usually associated with front and rear followers which co-operate with stop lugs on the draft sills, the followers being also disposed within the yoke and co-operating respectively with the butt end 19 of the drawbar and the abutment surface 25 of the rear end section 15 of the yoke. It will be evident that when the yoke has the shock absorbing mechanism and followers assembled therewith, the drawbar will be yieldingly maintained in its outermost position as shown in Figure 1, thereby holding the butt 19 seated in the slot 22 of the locking member C so that displacement in a transverse direction of the locking element will be prevented.

In assembling the drawbar B with the yoke A, the butt 19 of the drawbar is passed through the opening at the forward end of the hood of the yoke, the distance between the flange 16 and the bottom wall 15 of the hood being such as to permit free insertion of the butt 19 of the drawbar as hereinbefore pointed out. Due to the fact that the bottom arm 11 of the yoke is downwardly offset as shown at 17, the drawbar butt will pass freely between the top and bottom walls of the hood until the butt section of the drawbar is disposed entirely within the hood. The drawbar is then moved rearwardly within the yoke a sufficient distance for the lower

abutment shoulder 20 to clear the rear end of the slots 18 in the side walls of the hood. It will be evident that when the drawbar butt is in the last named position, the locking block or element C may be freely inserted in a transverse direction through the slots 18. When the drawbar and the yoke have been thus far assembled, the locking element or block C is inserted through the slots 18 until the slot 22 thereof is disposed midway between the side walls 14 of the yoke. The drawbar B is then pulled forwardly, locking the lower portion of the butt 19 thereof within the slot 22 of the locking block C. It will be evident that the locking block will thus be positively held against transverse displacement and that outward movement of the drawbar will be positively limited by the shoulders 20 of the butt section 19 thereof engaging the flange 16 at the upper side of the hood and the flange 21 on the locking block C. With the draft gear assembled within the yoke as hereinbefore explained, the drawbar will be yieldingly maintained in its outermost position, thereby effectively interlocking the same with the block to prevent lateral displacement of the latter with reference to the yoke, the key in turn holding the drawbar assembled with the yoke.

From the preceding description taken in connection with the drawbar, it will be evident that I have provided a simple and efficient expedient for holding the drawbar and yoke assembled together with means for preventing accidental displacement of the locking element. By providing the interlocking drawbar butt and key or locking block, the use of auxiliary means for preventing lateral displacement of the locking block, such as cotter pins or bolts is entirely dispensed with and a more durable and reliable locking means for the key is provided. Inasmuch as the lower section of the butt 19 of the drawbar co-operates with the shoulders 23 to prevent lateral displacement of the locking member of my improved device, there is no danger of the parts wearing away, thereby permitting the locking element to become accidentally displaced with the resultant failure of the holding means for the drawbar butt, allowing the drawbar to become disconnected from the yoke.

While I have herein shown and described what I now consider the preferred manner of carrying out my invention, the same is merely illustrative, and I contemplate all the changes and modifications that come within the scope of the claims appended hereto.

I claim:

1. In a device of the character described, the combination with a drawbar having a butt presenting transverse shoulders; of a hooded yoke element having side, top, and bottom walls enclosing said butt, said walls for preventing transverse displacement of the

5 said butt, said hood having a transverse shoulder co-operating with one of said shoulders of the drawbar to prevent outward movement of said drawbar with reference to the yoke, said side walls having aligned openings, said drawbar butt being insertible through the front end of the hood; and a retaining member fitted within said openings held against displacement longitudinally of the yoke by 10 the front and rear end walls of said openings, said member having a transverse shoulder co-operating with the remaining shoulder of the drawbar to limit outward movement of the latter, said member having spaced upward standing side flanges co-operating with the side faces of the butt end of the drawbar to maintain said retaining member assembled with the yoke against the lateral removal.

2. In a device of the character described, 20 the combination with a yoke; of a drawbar having the butt end thereof fitted within the head of the yoke; and means for detachably connecting the drawbar and yoke, including a locking element, said yoke having means 25 thereon co-operating with said locking element to hold the same against displacement longitudinally of the yoke, but permitting lateral adjustment thereof, said drawbar butt when in assembled position with said yoke 30 interlocking with the locking element to positively prevent lateral displacement thereof.

3. In a device of the character described, 35 the combination with a yoke open at the head end thereof; of a drawbar having the butt end thereof fitting within the head of the yoke, said butt end being freely insertible through the open end of the yoke head; of a detachable element restricting said opening of the yoke head to hold the drawbar to the yoke; 40 and means on said yoke for holding said detachable element against displacement in a direction lengthwise of the yoke, but permitting lateral adjustment of said member to assemble the same with the yoke, said member having means co-operating with the drawbar butt adapted to interengage with the latter when in assembled position with said yoke for preventing relative lateral displacement 45 of said drawbar and member to retain said member against lateral removal from the yoke.

4. In a device of the character described, 50 the combination with a drawbar having a shouldered butt; of a yoke having a hooded front end having top, bottom and side walls adapted to receive the shouldered drawbar butt, said side walls being provided with aligned openings; a removable shouldered locking block within the hood extending through said openings and adapted to engage a shoulder of the drawbar butt to hold the drawbar assembled with the yoke, said block having upstanding shoulders embracing the 55 sides of the drawbar butt to prevent displace-

ment of said locking block and accidental removal thereof.

5. A yoke for draft riggings formed at its forward end to receive a drawbar butt therewithin; and a removable locking block 70 adapted to engage a shoulder on the drawbar, said yoke being transversely slotted to receive the locking block and said block being recessed in a direction lengthwise of the yoke to receive the drawbar butt to interlock the 75 block with said drawbar and yoke against lateral displacement.

6. A yoke for railway draft riggings having a head at the forward end thereof adapted to receive the shouldered butt of a drawbar 80 and a flanged locking block for holding the drawbar attached to the yoke, the flange of said block interlocking with a shoulder of said drawbar, the head of said yoke being transversely slotted to accommodate the block 85 and said block being recessed to provide a seat to receive the butt of the drawbar in interlocking relation with the yoke.

7. In a hooded yoke, the hood of which is adapted to receive the butt end of a drawbar provided with a shouldered butt member; a locking element having a transverse shoulder adapted to engage the shouldered portion of the drawbar butt to limit the outward movement of the drawbar with respect to the yoke and hold the same assembled therewith, the hood portion of the yoke being provided with side openings through which the locking element is insertible, the ends of said locking element fitting the openings to hold said element against longitudinal movement with respect to the yoke, said locking element having side flanges partially embracing the drawbar butt on opposite sides thereof to lock the retaining element to the drawbar 100 and prevent lateral displacement and removal of the same when the parts are assembled.

8. In a yoke having a hooded forward end adapted to receive a drawbar butt having transverse abutment shoulders, said yoke being provided with transverse abutment shoulders, and a locking block disposed between said shoulders and held against longitudinal movement with respect to the yoke by said abutment shoulders, said locking 105 block having a transverse shoulder engaging one of said transverse abutment shoulders of the drawbar butt to hold said drawbar assembled with the yoke and limit outward movement thereof with respect to the yoke, 110 said block having side flanges partially embracing the sides of the butt.

9. In a yoke having a hooded forward end adapted to accommodate a shouldered drawbar butt, and a locking block, said hood and locking block having co-operating abutment faces limiting forward movement of the block with respect to the yoke, said locking block having a transverse shoulder and side flanges, said transverse shoulder engaging 115 120 125 130

the shouldered portion of the drawbar butt to hold the drawbar assembled with the yoke and limit outward movement thereof, and said side flanges partially embracing the sides of the drawbar.

5 10. As an article of manufacture, a locking block adapted for use with a coupler having a shouldered butt and a hooded yoke, said block having a main body portion provided with a transverse, rearwardly facing shoulder adapted for cooperation with the coupler butt shoulder; vertically disposed side wings adapted to partly overlap the opposite, lateral sides of the coupler butt inwardly 15 of said shoulder, said wings being fixed with respect to each other and rigid with the main body portion of the block; and forwardly facing abutment means adapted for cooperation with rearwardly facing abutment 20 means on the yoke.

26 In witness that I claim the foregoing I have hereunto subscribed my name this 16th day of December, 1926.
